UNITED STATES PATENT OFFICE.

JAMES N. LYLES, OF OAKCREST, VIRGINIA, ASSIGNOR TO JOANNA MERCHANTILE COMPANY, OF GOLDFVILLE, SOUTH CAROLINA, A CORPORATION OF SOUTH CAROLINA.

DESIGN FOR A TOKEN.

Application filed May 6, 1929. Serial No. 31,107. Term of patent 7 years.

To all whom it may concern:

Be it known that I, JAMES N. LYLES, a citizen of the United States, residing at Oakcrest, Arlington County, Virginia, have invented a new, original, and ornamental Design for Tokens, of which the following is a specification, reference being had to the accompanying drawing, forming a part thereof.

Figure 1 is a side elevation of a token embodying my design, and,

Figure 2 is an edge elevation of the same.

I claim:

The ornamental design for a token, as shown.

JAMES N. LYLES.
